ATTORNEY

Patented Feb. 16, 1926.

UNITED STATES PATENT OFFICE.

PAUL CHARLES LABASSE, OF NEW ORLEANS, LOUISIANA.

CALIPER.

Application filed September 15, 1923. Serial No. 662,914.

To all whom it may concern:

Be it known that I, PAUL C. LABASSE, a citizen of the United States, residing at New Orleans, in the parish of Orleans and State of Louisiana, have invented new and useful Improvements in Calipers, of which the following is a specification.

This invention relates to a self-centering micrometer caliper, especially designed for obtaining diameters of three winged valves or other three winged or fluted objects, an object being to provide a three point gauge so as to determine the diameter of an opening for the accommodation of the object without the necessity of feeling for a center and without calculations.

Another object of the invention is to provide a micrometer caliper for the above stated and other purposes, by means of which diameters may be readily and accurately obtained.

With the above and other objects in view, the invention further includes the following novel features and details of construction, to be hereinafter more fully described, illustrated in the accompanying drawings and pointed out in the appended claims.

In the drawings:—

Figure 1 is an elevation illustrating the use of the invention.

Figure 2 is a vertical sectional view of the same.

Referring to the drawings in detail wherein like characters of reference denote corresponding parts, the reference character 1 indicates an arm which includes a curved portion 1^a and an angular extremity 1^b whose included angle in the present case is sixty degrees. Secured to the arm 1 is a barrel 2 whose bore is provided with a reduced threaded portion 3 for the reception of an exteriorly and interiorly threaded nut or sleeve 4. The nut or sleeve 4 has threadedly engaged therewith a jam nut 5, or lock nut 5, the outer periphery of which is tapered for engagement with the walls of a similarly tapered portion 5^a of the barrel bore.

Extending around and over the barrel 2 is a sleeve 6 whose outer end is closed and has secured thereto the threaded portion 7 of a spindle 8. The threads 7 engage the threads upon the interior of the sleeve or

nut 4 and are threaded 26 $\frac{2}{3}$ threads to the inch, for a purpose to be later apparent. The outer end of the spindle 8 is provided with a threaded socket 9 so as to provide for removable engagement with the threaded stud extending from the end of a range pin 10. A number of different range pins are employed for obtaining different diameters. The pins are graded "0 to 1"; "1 to 2"; and "2 to 3" and are faced flat at their ends 11 to their proper lengths to come in contact with standard diameters, such as 1" 2" and 3" diameters, when said diameters are engaging the opposite inner faces of the 60° angle and when the sleeve 6 is set at zero. When placed in position at the end of the spindle, the markings 12 on the pin and spindle will register when the faces between the spindle and pin are in proper contact.

The inner end of the sleeve 6 is beveled and is graduated as indicated at 13, there being twenty-five divisions around its circumference. In addition the barrel 2 is graduated as indicated at 14, the graduations being 26 $\frac{2}{3}$ to the inch, or 40 graduations to 1 $\frac{1}{2}$ inches extending along a line parallel with the axis of the barrel.

Assuming that the figure represented at A in Figure 1 represents a three winged valve or other three winged or three fluted object placed within the instrument and that its diameter is 2 $\frac{1}{8}$ ". A range pin used for measuring diameters from 2 to 3" is secured to the end of the spindle and the object is arranged so that the end 11 of the range pin engages one wing, while the other two wings engage the opposite inner faces of a 60 degree angle. The distance from the center C of the object to the apex D of the angle will equal the diameter of the object, while the distance from the point 11 of the range pin to the apex D of the angle is equal to 1 $\frac{1}{2}$ times the diameter of the object. Since the range pin 10 is made to receive the 2" standard diameter when the sleeve 6 is set at zero, it would only be necessary to unscrew or move the sleeve outward five turns to raise the spindle .1875, (that being the pitch of the screw multiplied the number of turns of the sleeve) or .0375 $\times$ 5 equals $\frac{1}{16}$ of an inch, the amount the spindle should raise in order to bring the range pin

in contact with a $2\frac{1}{8}$ " circle, or $\frac{1}{8}'' \times 1\frac{1}{2}''$ equal $\frac{3}{16}$ ". The thimble 6 will then show a reading to the fifth line or $\frac{125}{1000}$ as an ordinary micrometer or a $2\frac{1}{8}$ " diameter. The relation between the angle and the screw is proportionate and readings to a $\frac{1}{1000}$ part of an inch can easily be obtained. This caliper may be made to measure 3" diameters or larger. To change the range it is only necessary to screw down the thimble 6 to its zero position and change the range pins as required.

Wear of the threads on the spindle 8 may be compensated for by tightening the jam nut and raising or lowering the spindle to a standard diameter by screwing or unscrewing the nut or sleeve 4.

The invention is susceptible of various changes in its form, proportions and minor details of construction and the right is here reserved to make such changes as properly fall within the scope of the appended claims.

Having described the invention what is claimed is:—

- 25 1. A micrometer caliper comprising a barrel, an arm extending from the barrel and terminating in an angular extremity with the apex of the angle in line with the axial center of said barrel, a sleeve movable upon the barrel, there being cooperating graduations upon the sleeve and barrel, an adjusting nut threadedly engaging the bore of the barrel, a spindle secured to the sleeve and extending through and threadedly engaging

the nut and a range pin detachably secured to the spindle.

2. A micrometer caliper comprising a barrel provided with a bore having a tapered portion, an arm extending from the barrel and terminating in an angular extremity with the apex of the angle in line with the axial center of said barrel, a sleeve movable upon the barrel, there being cooperating graduations upon the sleeve and barrel, an adjusting nut threadedly engaging the bore of the barrel, a spindle secured to the sleeve and extending through and threadedly engaging the nut and a tapered jam nut threadedly engaging the adjusting nut and located within a tapered portion of the bore of the barrel and a range pin detachably secured to the spindle.

3. A micrometer caliper comprising a barrel, an arm extending from the barrel and terminating in an extremity having an included angle of sixty degrees, with the apex of the angle in line with the axial center of said barrel, a sleeve movable upon the barrel, there being cooperating graduations upon the sleeve and barrel, an adjusting nut threadedly engaging the bore of the barrel, a spindle secured to the sleeve and extending through and threadedly engaging the nut and a range pin carried by the spindle.

In testimony whereof I affix my signature.

PAUL CHARLES LABASSE.
